CAN OPENER

Wayland J. Noblett, Long Beach, Calif.

Application May 20, 1947, Serial No. 749,200

8 Claims. (Cl. 30—8)

1

This invention relates to improvements in can opening devices and more particularly to an improved can opener which is supported on the can during the opening operation rather than being supported on a wall or a table, and is operated by a hand crank so that a can top may be completely severed from a can with a minimum of manual effort.

It is among the objects of the invention to provide an improved can opener or simplified construction which is economical to manufacture, has a minimum number of different parts, is easy to apply in operative position to a can to be opened, engages the can in a positive and effective manner so that the can lid is severed from the can without slipping of the opener, which leaves the end of the can in a smooth condition without any sharp or protruding pieces of metal which might injure the hand of a person using the opener or handling the can, which is effective to efficiently remove the end closure or lid from a can with an extremely small amount of manual effort and without loss of time, and which is so constructed as to be capable of opening an extremely large number of cans without requiring any servicing or repair.

Other objects and advantages will become apparent from a consideration of the following description in conjunction with the accompanying drawings wherein:

Fig. 1 is a side elevational view of the improved can opener shown applied in operative position to a can to be opened;

Fig. 2 is a longitudinal sectional view of the can opener taken on the line 2—2 of Fig. 3;

Fig. 3 is an end elevational view of the can opener looking at the left hand end as viewed in Fig. 1;

Fig. 4 is a transverse sectional view taken on the line 4—4 of Fig. 1; and

Fig. 5 is a detailed sectional view of a fragmentary part of the can opener taken on the line 5—5 of Fig. 1.

With continued reference to the drawings, the can opener comprises a body or frame 10 which may be conveniently formed of a single length of suitable strip or strap metal bent to the appropriate shape. This frame comprises a substantially straight base portion 11 having at one end thereof a depending foot portion 12 disposed substantially at right angles to the portion 11 and providing a rest or abutment for operative association with the side of a can in the manner illustrated in Fig. 1. At the end of the

base portion 11 opposite the foot 12 the strip is bent at right angles to provide a vertical outer leg portion 13 and from the upper end of the portion 13 is curved around a quadrant 14 to the upper end of a vertical standard portion 15 which is positioned immediately above the top edge of the can when the opener is in operative position. At the lower end of the vertical standard portion 15 the strap is bent at right angles to provide a horizontal guide portion 16 which extends inwardly towards the outer leg 13 and at the inner end of this portion 16 the strap is again bent downwardly at right angles to provide the inner leg 17 the end portion of which is bent outwardly at right angles to provide a foot 18 which is secured to the base member 11 intermediate the length of the base member by suitable means, such as the screws 19.

The outer and inner leg portions 13 and 17 are provided with registering internally screw threaded apertures which receive an externally screwthreaded sleeve 20 having oppositely disposed wings 21 on the outer end thereof.

A shaft 22 is rotatably mounted in the sleeve 20 and is bent at its outer end to provide a crank 23 upon which is secured a rotatable handle 24. A washer 25 loosely surrounds the shaft 22 at the inner end of the sleeve 20 and is provided with a partly spherical outer face 26 and a depending spoke or lever member 27 the lower end of which engages one side of the base portion 11 of the frame to restrain the washer against rotation. A can turning disk 28 is fixed upon the inner end of the shaft 22, the disk having a centrally located square or other noncircular aperture and the shaft having a correspondingly shaped end portion 29 which is received in the disk aperture and expanded to firmly secure the wheel or disk 28 on the end of the shaft. The outer face of the disk 28, that is, the face adjacent the can 30, is provided with radial teeth or serrations 31 which operatively engage the upper rim 32 of the can to rotate the can when the shaft 22 is turned by the crank 23.

The horizontal guide portion 16 is provided with a rectangular aperture 33 adjacent the standard portion 15 into which aperture the upper portion of the disk 28 extends, as is illustrated in Fig. 2.

A blade 34 having a sharpened and pointed lower end is secured to the inner surface of the standard portion 15 by suitable screw fasteners 35 and extends downwardly through the aperture 33 so that its edged and pointed lower end

is opposite the serrated face of the disk 28 and is spaced from the face of the disk a distance substantially equal to the thickness of the can rim 32.

A member 36 has a leg portion 37 secured to the outer surface of the standard portion 45 by the screw 35 and a magnetized portion 38 disposed at right angles to the leg portion 35 and is positioned adjacent to or in contact with the top or upper end closure of a can when the can opener is in operative association with the can. The magnetic portion 38 of this member 36 is preferably formed of a material capable of permanently retaining strong magnetism, the material "alnico" being particularly suitable for this purpose.

A hand knob 40 is secured to the top of the outer frame 14 by a suitable screw fastener 41 in a position substantially directly above the cutting blade 34.

The operation of the device is believed to be obvious from the drawings. The device is placed in position so that the point of the knife element 34 contacts the can top just within the can rim 32. Pressure is then applied to the knob 40 to force the point of the knife through the can top until the guide portion 16 contacts the upper edge of the can. The sleeve member 20 is then rotated by the wings 21 forcing the washer 26 against the rear or outer side of the disk 28 and in turn forcing the serrated face of the disk into firm engagement with the outer peripheral surface of the can rim 32. The shaft 22 is then rotated by the crank 23 and the disk 28, engaging the can rim, rotates the can causing the knife to sever the top end closure or lid of the can around the inner surface of the can wall.

When the end closure has been completely severed from the can it is attracted and held by the magnet 38 so that it does not drop down into the can.

The sleeve 20 is then rotated to relieve the pressure exerted on the disk 28 and the can opener may then be tilted slightly upwardly at its outer portions and lifted from the can, the can lid or cover adhering to the magnet 38 and being removed from the can at the same time.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed is:

1. A can opener comprising a continuous metal frame having a base portion arranged to contact a can wall at one end and extend substantially at right angles to said can wall, a pair of substantially parallel leg portions extending upwardly from said base portion, a guide portion overlying the upper end of the can, and a standard portion extending upwardly from said guide portion; a blade secured to said standard portion and extending downwardly through said guide portion; an externally screw threaded sleeve extending through internally threaded apertures in said leg portions; a shaft journalled in said sleeve and having a hand crank on the outer end thereof; a disk having a radially serrated inner face fixed on the inner end of said shaft in position to engage a can upper rim and rotate the can

against said blade; and a thrust washer interposed between the inner end of said sleeve and said disk whereby rotation of said sleeve in said leg portions will force said disk into operative engagement with said can rim.

2. A can opener comprising a continuous metal frame having a base portion arranged to contact a can wall at one end and extend substantially at right angles to said can wall, a pair of substantially parallel leg portions extending upwardly from said base portion, a guide portion overlying the upper end of the can and a standard portion extending upwardly from said guide portion; a blade secured to said standard portion and extending downwardly through said guide portion; an externally screw threaded sleeve extending through internally threaded apertures in said leg portions; a shaft journalled in said sleeve and having a hand crank on the outer end thereof; a disk having a radially serrated inner face fixed on the inner end of said shaft in position to engage a can upper rim and rotate the can against said blade; and a thrust washer interposed between the inner end of said sleeve and said disk whereby rotation of said sleeve in said leg portions will force said disk into operative engagement with said can rim and a member of magnetic material secured to said standard portion and overlying the top end closure of said can.

3. A can opener comprising a continuous metal frame having a base portion arranged to contact a can wall at one end and extend substantially at right angles to said can wall, a pair of substantially parallel leg portions extending upwardly from said base portion, a guide portion overlying the upper end of the can and a standard portion extending upwardly from said guide portion; a blade secured to said standard portion and extending downwardly through said guide portion; an externally screw threaded sleeve extending through internally threaded apertures in said leg portions; a shaft journalled in said sleeve and having a hand crank on the outer end thereof; a disk having a radially serrated inner face fixed on the inner end of said shaft in position to engage a can upper rim and rotate the can against said blade; and a thrust washer interposed between the inner end of said sleeve and said disk whereby rotation of said sleeve in said leg portions will force said disk into operative engagement with said can rim; and a hand knob secured to said frame near the upper end of said standard for forcing said blade into the top end closure of the can and for supporting said can opener during the opening operation.

4. A can opener comprising a narrow frame having a three sided inner portion of rectangular shape and an outer portion of substantially quadrant shape spaced from said inner portion and connected thereto at its ends; a blade extending inwardly of said inner portion at one side of the open end thereof, an externally screw threaded sleeve extending into said inner portion at the closed side thereof and supported in internally screw threaded apertures in said inner and outer frame portions, a shaft journalled in said sleeve and having a hand crank, on the outer end thereof, a disk member having a radially serrated face fixed on the inner end of said shaft, and a thrust washer between said disk and the inner end of said sleeve, whereby rotation of said sleeve in said frame will move said disk toward said blade or free said disk for movement away from said blade.

5. A can opener comprising a generally angular frame having two portions disposed substantially at right angles to each other, a blade secured to the outer end of one frame portion and projecting into the space included between said two portions, an externally screw threaded sleeve rotatably mounted in the other of said frame portions and disposed substantially parallel to said one frame portion with its inner end extending into the space between said two frame portions, a shaft journaled in said sleeve and having a hand crank on the outer end thereof, and a disk on the inner end of said shaft having a radially serrated face adjacent the portion of said blade projecting into said space.

6. A can opener as defined in claim 5 including a support member extending from the outer end of the other of said frame portions across the end of said space opposite said one frame portion.
- 5 7. A can opener as defined in claim 5 including a hand knob secured on said one frame portion near the outer end thereof.
- 10 8. A can opener as defined in claim 5 wherein said frame comprises a continuous narrow metal strip bent to provide inner and outer angular frame parts.
